MARDER, HUSE, & CO.

Chicago.

UNITED STATES PATENT OFFICE.

CARL MÜLLER, OF CHICAGO, ILLINOIS, ASSIGNOR TO MARDER, LUSE & CO.,
OF SAME PLACE.

DESIGN FOR PRINTING-TYPE.

SPECIFICATION forming part of Design No. 13,161, dated August 8, 1882.

Application filed June 20, 1882. Term of patent 7 years.

To all whom it may concern:

Be it known that I, CARL MÜLLER, a citizen of the United States of America, residing at Chicago, in the county of Cook and State 5 of Illinois, have invented and produced a new and original Design for a Fout of Printing-Type, which I designate "Normandy," of which the following is a specification, reference being had therein to the accompanying typographic 10 impressions of the same.

My new design consists of an alphabet of lower-case and capital letters, with numerals, punctuation-marks, beginning, central, and end pieces, as shown.

15 The general character of the new design may be described as consisting of light, medium, condensed, ornamental letters, having their lines scrolled and ending with light dots either at their beginning or termination, or 20 both.

The lower-case letters k, i, j, o, v, and w and the capitals V and W are peculiarly formed, k having its lower slanting line extended upward across the upper slanting line at a point 25 about one-eighth ($\frac{1}{8}$) of the length of the letter, i and j having star-shape dots, o having cen-

tral slanting parallel lines, the lower-case and capital letter V having the downward strokes extended across each other about one-third ($\frac{1}{3}$) of the length of the letter from the bottom, 30 and a horizontal line connecting the points of those downward strokes, forming a triangle, and the lower-case w having its lower and upper central parts and the capital W its lower parts formed like the lower parts of the letter 35 V. The capital D is provided with an ornament, as shown, and the capitals I, N, O, Q, U, X, and Y have connected with them ornaments, terminating in scrolls and light dots.

What I claim as new, and desire to secure 40 by Letters Patent, is—

The new design for a font of printing-type, having the letters, numerals, and ornaments formed as herein described, and as shown in the printed specimens.

45 In testimony whereof I affix my signature in presence of two witnesses.

CARL MÜLLER.

Witnesses:

AMOS DRESSER,
A. P. LUSE.
